UNITED STATES PATENT OFFICE.

NILS FREDERICK AMBURSEN, OF BROOKLINE, MASSACHUSETTS.

CLOTHES-POUNDER.

1,089,808.

Specification of Letters Patent. Patented Mar. 10, 1914.

Application filed September 11, 1913. Serial No. 789,322.

To all whom it may concern:

Be it known that I, NILS FREDERICK AMBURSEN, a citizen of the United States, and a resident of Brookline, in the county of Norfolk and State of Massachusetts, have invented a new and useful Improvement in Clothes-Pounders, of which the following is a specification.

My invention relates to clothes-pounders and its object is to improve the construction thereof in the manner hereinafter set forth.

Three embodiments of my invention are illustrated in the drawings which accompany and form a part of this specification; but it will be understood that various modifications may be made in the devices shown without departing from the spirit of my invention.

In the drawings: Figure 1 is a vertical section of my improved clothes-pounder; Fig. 2 is a vertical section of a modification; Fig. 3 is an inverted plan view of the device shown in Fig. 1; Fig. 4 is a vertical section of a further modification; Fig. 5 is a section on the line 5—5 of Fig. 4; and Fig. 6 is a section on the line 6—6 of Fig. 4.

In the particular drawings selected for more fully disclosing my invention, 1 represents a conical body of tin or other suitable material having an imperforate elastic diaphragm 2, preferably of pure rubber, secured to the interior wall thereof at a point intermediate its ends. The means for securing the diaphragm to the conical body consists, as shown in Fig. 1, of a metallic ring 3 shaped to conform to the inclination of the wall of the body 1 and split at 4, the downturned edges 2' of the diaphragm, which are preferably corrugated as shown at 5, being clamped between the interior wall of the conical body and ring, the outer face of which preferably is correspondingly corrugated, as shown at 6, and held in position by the screws or rivets 7. It will be obvious that various means may be employed to secure the diaphragm to the interior of the conical body. Where the split ring 3 is employed, the screw or rivet diametrically opposite to the split 4 is first placed in position and then other screws or rivets are inserted on either side until the split is reached, the split enabling the ring to conform more perfectly to the inclination of the wall of the conical body 1. It is highly desirable to make an air-tight joint between the diaphragm and cone and for this purpose I

prefer to corrugate the downturned edges of the diaphragm and the outer face of the ring, as shown. In order to prevent the clothes from rising up into the cone I provide a grating consisting in the present instance of the ribs 8, having the flanges 10 secured to the ring 9 by the rivets or screws 9', or by soldering or otherwise, and said ring may be secured to the conical body 1 below the diaphragm in any suitable manner, as for example, by means of said rivets or screws passing through the walls of said body as shown, or by soldering or otherwise. The inner ends of the ribs may be united as shown at 11 by soldering or in any other suitable manner. The conical body terminates in a tube 13 preferably tapering upwardly, and a hollow handle 12 of brass or other suitable material, the lower portion of which is correspondingly tapered, is fitted over said tube.

In the operation of clothes-pounders of this general type, the up-stroke creates suction and the down-stroke forces air and water through the clothes. By means of the improvement above described, I am enabled very effectually to force a considerable quantity of air and water through the clothes on the down-stroke. As will be obvious, on the down-stroke the compression of the air in that portion of the cone below the diaphragm will flex the latter upwardly, the air above the diaphragm passing out through the hollow handle 12, so that at the end of the stroke the diaphragm will react and momentarily bulge downwardly beyond its normal position, thereby driving an additional amount of air and water through the clothes with considerable force. On the up-stroke, a certain amount of suction will be created, thereby drawing a new charge of air into the cone below the diaphragm and the diaphragm will be flexed downwardly, air now passing into the upper portion of the cone through the hollow handle. At the end of the upstroke the reaction of the diaphragm upwardly into and beyond its normal position will greatly increase such suction, so that in the next down-stroke a considerable amount of air and water will be forced through the clothes as above described.

In the modification shown in Fig. 2, a diaphragm 14, preferably of thicker rubber than the diaphragm 2 of Fig. 1, is secured in any suitable manner across the cone

1, as for example by means of the ring 15 and screws 16 which pass through said cone and ring. In this case the hollow handle 17, the lower portion of which is provided 5 with perforations 18, and which has the collars 19, 19' secured to it to limit its movement with respect to the cone, is attached at its lower end to the diaphragm by means of the washers 22 and nut 23, or in any other 10 suitable manner, so as to make an air-tight joint between the diaphragm and handle. The cone 1 terminates in a tube 20 to which is secured by soldering or otherwise, a sleeve 20' having a cap 20'', and between the cap 15 and collar 19' is interposed a spiral spring 21, the spring and collar being so arranged that in normal position the diaphragm is flexed upwardly, as shown. The cap 20'' should preferably fit the handle snugly so 20 as to make the bearing water-tight. A grating 24 consisting of ribs 24 is attached to the lower end of the cone in any suitable manner, the inner ends of the ribs being united at 25. It will be understood, of course, that 25 the form of grating shown in Fig. 1 may be used in the modification illustrated in Fig. 2 and vice versa.

In the operation of the clothes-pounder shown in Fig. 2, the movement of the conical body on the down-stroke will force air and water through the clothes and at the 30 end of the down-stroke, or shortly before, the relative movement of the handle and cone against the tension of the spring 21 will flex the diaphragm downwardly, thereby forcing an additional amount of air and water through the clothes. On the up-stroke the suction created will be increased 35 by the reaction of the diaphragm and spring. In this case the air in the conical body above the diaphragm will escape through the hollow handle by way of the perforations 18 when the diaphragm is flexed upwardly, and will enter said portion 40 when the diaphragm is flexed downwardly.

It will be obvious that in all three embodiments of my invention there is no possibility of any compression of air in the space above the diaphragm and therefore no interference with the free action of the latter under the influence of compression and rarefaction in the lower part of the cone. The 50 cone may be provided with vent-holes 1', 1', so as to raise the level to which the water 55 will rise in the cone on the down-stroke.

In the modification shown in Fig. 4 the downturned edges 2'' of the diaphragm 2 are held in position in the groove 26 of the conical body by means of the spring-ring 60 27 provided with downwardly-extending finger-pieces 28, whereby, as will be obvious,

the ring may be contracted in diameter, inserted over the downturned edges of the diaphragm and then sprung into position.

If desired, a wedge-shaped key 30 having 65 its outer edges channeled to receive the finger-pieces 28 may be employed to prevent the dislodgment of the ring during the operation of the clothes-pounder. In such case the lower ends of the finger-pieces may be 70 off-set as shown, at 29, and after the ring has been placed in position the two finger-pieces are bent away from each other, the key inserted and the finger-pieces allowed 75 to snap back over the same, thereby securely locking the ring in position.

I claim:

1. A clothes-pounder comprising a conical body and an imperforate elastic diaphragm secured to the interior wall of said body at 80 a point intermediate the ends thereof.

2. A clothes-pounder comprising a conical body, an imperforate elastic diaphragm secured to the interior wall of said body at 85 a point intermediate the ends thereof, and a grating arranged below said diaphragm.

3. A clothes-pounder comprising a conical body an imperforate elastic diaphragm secured to the interior wall of said body at 90 a point intermediate the ends thereof, and a hollow handle for operating said clothes-pounder.

4. A clothes-pounder comprising a conical body, and an imperforate elastic diaphragm secured to the interior wall of said 95 body at a point intermediate the ends thereof, the wall of said body being provided with a vent-hole below said diaphragm.

5. A clothes-pounder comprising a conical body, an imperforate elastic diaphragm 100 secured to the interior wall of said body at a point intermediate the ends thereof, a hollow handle secured to said diaphragm, and resilient means for normally maintaining said diaphragm flexed upwardly.

6. A clothes-pounder comprising a conical body, an imperforate elastic diaphragm secured to the interior wall of said body at a point intermediate the ends thereof, a hollow handle secured to said diaphragm, 110 means for limiting the movement of said handle relatively to said body, and resilient means for normally maintaining said diaphragm flexed upwardly.

In testimony whereof, I have hereunto 115 subscribed my name this 9th day of September, 1913.

NILS FREDERICK AMBURSEN.
